UNITED STATES PATENT OFFICE.

WILLIAM J. O'SULLIVAN AND WILLIAM D. WATSON, OF LOUISVILLE, KENTUCKY.

WEATHER-STRIP.

No. 895,674.

Specification of Letters Patent.

Patented Aug. 11, 1908.

Application filed August 6, 1906. Serial No. 329,392.

To all whom it may concern:

Be it known that we, WILLIAM J. O'SULLIVAN and WILLIAM D. WATSON, citizens of the United States, residing at Louisville, in the county of Jefferson and State of Kentucky, have invented a new and useful Weather and Dust Strip, of which the following is a specification.

Our invention relates to improvements in weather stripping for windows, doors, transoms and other such like openings and the objects of our inventions are, first, to provide a packing for the spaces that ordinarily occur between sash or doors and their frames for the purpose of preventing the passage through these openings of air, water, dust, smoke, fog, vapor, hail, snow, frost, rain, soot, dirt, or any other foreign substance desired to be excluded; from the interior of buildings, cars, water craft and other such like structures; and second, to provide for windows a system of weather stripping that packs tightly all the spaces ordinarily occurring around the sash, automatic in its action, easy to operate, concealed from view, and unnecessary to remove for any purpose except repairs. We attain these objects in the manner illustrated in the accompanying drawings in which—

Figure 1, is an outside elevation of an ordinary box frame window showing the pulley stiles, head and sill of frame in section. Fig. 2, is a top view of upper sash. Fig. 3, is a side view of upper and lower sash. Fig. 4, is a side elevation of weather strip for sides of sash shown as for sash B. Fig. 5, is a cross-section on line 5—5 of Fig. 4. Fig. 6, is a section of Fig. 4 taken on line a—a. Fig. 7, is a side elevation of weather strip for top and bottom and meeting rail of sash. Fig. 8, is an end view of Fig. 7. Fig. 9, is a side view of toe pocket. Fig. 10, is a back view of toe pocket, Fig. 11, is a side view of heel pocket. Fig. 12, is a front view of heel pocket. Fig. 13, is a part elevation of sash open with weather strip in place. Fig. 14, is a part elevation of sash closed with weather strips in place. Fig. 15, is a section on line b—b of Fig. 13. Fig. 16, is a section on line c—c of Fig. 14. Fig. 17, is a section on line d—d of Fig. 13. Fig. 18, is a section on line e—e of Fig. 14. Fig. 19, is a section on line f—f of Fig. 14. Fig. 20, is a section through meeting rail of sash closed. Fig. 22, is a striking plate for end of strip. Fig. 21 is a horizontal section through stile of sheet metal sash.

Similar letters refer to similar parts throughout the several views.

The sash A and B have grooves g cut in edges adjacent pulley stiles and between cord 60 grooves k and face of sash. The sash A has a groove h cut in top rail in edge adjacent head of frame between cord grooves k and face of sash. The sash A has a groove l cut in meeting rail in edge adjacent meeting rail of sash 65 B. The sash B has a groove m cut in lower rail in edge adjacent sill. In connection with grooves g in sash are cut mortises i. In pulley stiles C are cut mortises J.

The weather strip Fig. 4 is composed of a 70 metal strip D bent lengthwise U shape and with lower end turned and soldered so as to form a solid striking end; second a felt, rubber, or asbestos strip E doubled lengthwise and inserted between sides of metal strip 75 with cushion edge outward and fastened in place; and third, metal blades F projecting through slits in metal strip and cushion strip and attached rigidly to metal strip. The edges o and p of blade F incline downward in 80 manner to fit between surfaces r and s of Fig. 9. The rounded edge q of blade F fits into concave side t of Fig. 11. The toe pocket Fig. 9, is inserted into mortises i of sash B and is attached to sash with screws through holes 85 u; the heel pocket Fig. 11, is inserted into mortises j of pulley stiles and is attached with screws through holes v. The sash B being removed from between pulley stiles has inserted into its grooves g the 90 weather strip Fig. 4, with blades F entered into pocket Fig. 9, with lower end w projecting below bottom of sash, and with rounded edge q flush with edge of sash. (Fig. 17.) The sash being put back into place in a raised 95 position and then closed down; the end w of weather strip strikes the plate on sill at x causing the edge o of blade to slide t on the surface r of toe pocket and the rounded edge q to enter the heel pocket at t with the 100 result that the cushion E comes in contact with the surface G of pulley stile, spreading and packing tight the space H between sash and pulley stile. When the sash B is again raised the surface s of toe pocket impinges 105 upon the edge p of the blade, forcing the rounded edge q against the upper portion of the concave surface t of the heel pocket, causing the blade to come out of the heel pocket and reenter the toe pocket thereby carrying 110 the weather strip back to its original position and allowing the sash to slide up freely.

The weather strip in upper sash A operates in the same manner as in the lower sash B except in a reversed position, the projecting end *w* striking the plate at head of window frame.

5 The grooves *h* at top of window *l* at meeting rails and *m* at bottom of window have inserted into them weather strips Fig. 7, made in same manner as weather strips Fig. 10 4, with the exception that they have no blade and are fixed tightly in place in the grooves with a part of cushion projecting so as to jam tightly against head and sill of window and against meeting rail of opposite sash, packing 15 tightly any spaces that might there exist. (Fig. 19 and Fig. 20). Fig. 21, shows how this automatic concealed weather strip is to be applied to sheet metal sash showing groove provided for reception of weather 20 strip.

Doors, transoms and other such like openings are to be fitted in manner shown in Fig. 19.

We claim:

The combination with a frame for an opening, and a closure of a weather strip bar mounted movably on said closure and having a transverse blade secured thereto, said blade having a pointed end projecting on one side of said bar and a rounded end projecting beyond the other side of said bar, said closure and said frame having recesses respectively adapted to be engaged by said ends to move said bar longitudinally and laterally. 25 30
